UNITED STATES PATENT OFFICE.

JOHN PHILIP MORSE, OF PURLEY, ENGLAND.

FASTENING.

Application filed October 23, 1922. Serial No. 596,451.

To all whom it may concern:

Be it known that I, JOHN PHILIP MORSE, a British subject, residing at Trelaske, Highland Rd., Purley, in the county of Surrey, England, have invented certain new and useful Improvements in Fastenings, of which the following is a specification.

This invention relates to fastenings of the stud-and-eye type of the kind in which the 10 female member is formed in two parts having relative movement.

According to the invention, one part of the said female member is provided with means such as spring fingers adapted to engage beneath the head of the stud, and the second part of the said member is provided with means adapted to operate the said stud-engaging means on a relative axial movement of the two parts by means of a 15 surface formed on one of the operative elements which is inclined to the axis of the said member.

The accompanying drawing illustrates two 25 alternative embodiments of this invention by way of example wherein—

Fig. 1 shows a vertical central section of an assembled fastening.

Figs. 2 and 3 show sections of the two elements of the female member when freed.

30 Fig. 4 shows a plan of one element, and Figs. 5 and 6 illustrate modifications.

Referring now to the Figs. 1 to 4, the improved fastening comprises a headed stud 1 of the one part which is here shown as 35 mounted on a piece of fabric which may form part of a glove, garment, vehicle hood or the like. The female member of the other part comprises a circular cup-shaped body 2 also mounted on a piece of fabric, 40 and having an upper inturned rim 3, and the engaging and operating elements 4, 5 of the fastening housed within said body.

Referring now to the first-mentioned element 4, the engaging element comprises an 45 inverted cup-shaped member provided on its edge with a number of downwardly-extending fingers 6 having turned ends 7 adapted to engage beneath the head of the stud 1. The fingers are each provided with an inwardly-inclined portion 6^a adjoining an outwardly-extending shoulder 6^b and terminating in a bent or looped portion 6^c serving to increase the resilience with which the inturned end 7 is supported. The fingers 6 55 tend normally to open so as to release the head of the stud owing to the resilience of

their base portions; but they are positively held in engagement therewith in the position shown by means that will be herein-after described. Intermediate said fingers, 60 the member 4 is provided with a second series of spring fingers or tongues 8 having turned up ends 8^a for a purpose that will hereinafter appear.

The operating member 5 is generally 65 channel-shaped in cross section, and is adapted to slide axially of the fastening within the body 2, being prevented from separation by the inturned rim 3 of said body and the out-turned rim 9 on the said member 5.

The inner wall of the member 5 is provided with an inturned flange 10 which is 70 provided with three slots 11 for the reception of the fingers 8. The latter thus afford guides for the correct positioning and movement of the member 4 within the member 5, and the ends 8^a of the said fingers are turned up after the said parts have been fitted and thereafter serve as retaining means to prevent the separation of the two members. 75

Intermediate the said slots, the flange 10 is 80 cut away for the reception of the fingers 6, a small portion 12 of the flange 10, being, however, left in so as to serve as operating means for the fingers 6 as is clearly shown in Fig. 1. The ends of the said portions 12 engage with the outwardly-extending shoulders 6^b whereof the faces are so inclined that the two members of the female elements of the fastening are self-locking as against vibration or slight pressure, it being required to exert an appreciable amount of force to cause the portions 12 to become disengaged from the shoulder 6^b in the process of unlocking the fastening. The outer wall of 90 the member 5 is provided with inturned spring fingers 13 adapted to rest on the floor of the housing 2 and serve as return springs for the movement of the member 5.

It will be seen that when the female element of the fastening is desired to be engaged with the stud, all that is necessary is to press it over the head of the stud, whereupon the spring fingers 6 will be forced apart by the said head sufficiently to enable the fastening to be pressed home, the resilient loops 6^c of the fingers 6 permitting the ends 7 to be deflected and to pass beneath the head of the stud where they will be maintained in engagement by the fingers 12. If then it is desired to release the fastening, all that is necessary is to depress 110

the operating member 5 against the resilience of the fingers 13 whereupon the fingers 12 will move to such a position as will allow the inclined fingers 6 to move under the 5 resilience of their base portions into the position shown in Fig. 2 where they are out of engagement with the head of the stud which can then be withdrawn, the part 5 reassuming the position shown in Fig. 1 10 immediately it is freed. It will of course be apparent that in the release operation described, any movement of the member 4 induced by the release movement of the member 5 will be interrupted by the fingers 7 15 engaging the base plate of the body 2, whereupon the member 5 continues its movement for the release action.

It is to be observed that any attempt forcibly to withdraw the fastening without 20 operating the releasing member will be chiefly resisted by the shearing strength of the turned ends 7 of the fingers 6 engaging between the underside of the stud and the circular edge of the centre orifice 14 of the 25 base plate 15 of the cup-shaped member 2. This provides a strong resistance without tending to deform any of the operative parts of the mechanism in a manner that would make it no longer serviceable. The looped 30 portions 6^a in the fingers 6 provide a resilient means whereby, when the member 5 is forced downwardly and the fingers 12 are forced past the edges of the shoulders 6^b, the said shoulders can move inwardly with- 35 out permanently deforming the fingers 6 in the event of the ends 7 being held fixed by the stud 1. They also serve to interpose a resilient element between the male and female members of the fastening so as to avoid 40 permanent deformation of any of the parts in case of relative lateral movement.

It will be further noted that when the part 5 moves up into its normal position following the release of the fingers 7, the 45 portion 12 of the part 5 will engage the inclined portion 6^b of the fingers and will thereafter move the central part 4 upwardly with it to the full extent of movement, as the frictional engagement between the part 50 12 and the part 6^b is sufficient to overcome the gravitational influence on the part 4. The central part 4 will thus protrude upwardly from the annular part 5, and when it is desired to re-engage the stud, the part 4 55 will have to be positively depressed so as to bring the portion 6^a thereof to the same level as the part 12 of the member 5.

In a modification, I may substitute an annular ring for the operating fingers 12 60 as shown in Fig. 5.

The modification illustrated in Fig. 6 comprises a simplified model wherein the loops 6^a of the fingers 6 are dispensed with, and the fingers 8 and flange 10 are also dispensed 65 with, upwardly-extending lugs 16 on the

outer wall of the member 4 engaging in slots 17 in the inner wall of the member 5 serving to limit the movement of the member 5. The operating fingers 12 are four in number and are inclined downwardly as 70 shown and intermediate the fingers 6 in the member 4 are provided intervening fingers 18 adapted to rest on the head of the stud so normally as to urge the member 4 upwardly. 75

It will be realized that in both modifications the operation of the fastening depends upon an axial movement of one element of the female member operating through an inclined surface on the stud-engaging means. 80 In both forms shown the stud-engaging means are positively held in engagement with the stud and swing outwardly therefrom of their own resilience when released by the operating means. 85

Although primarily intended to be formed by press tools out of sheet metal, it is to be understood that this material is not essential to the invention, and I may form the fastening of such a size and strength that a lock 90 can be mounted within the cup-shaped annular member and operated through a key-hole facing upwardly in the drawing so as to force lateral bolts through the engaging rims 3 and 9 and through the engaging walls 95 of the members 4 and 5 so as to lock the fastening in its operative position.

I claim:

1. In a stud-and-eye fastening, a stud, a female member comprising an element having resilient stud-engaging fingers and an operating element capable of axial movement relatively to the stud-engaging element, an inclined surface on one of said elements, an element on the other of said elements engaging said inclined surface, the stud-engaging element being actuated by the operating element through the intermediary of the said inclined surface and of said element. 100

2. In a stud-and-eye fastening, a stud, a female member comprising an element having resilient stud-engaging fingers and an operating element capable of axial movement relatively to the stud-engaging element, an inclined surface on a stud-engaging finger and an element on said operating element engaging said inclined surface, the stud-engaging element being actuated by the operating element through the intermediary of the said inclined surface and of said element. 110

3. In a stud-and-eye fastening, a headed stud, a female member comprising an element having resilient stud-engaging fingers normally opened out so as to allow free passage to the head of the stud, an operating element capable of axial movement relatively to the stud-engaging element, inclined surfaces on said stud-engaging fingers, and means carried by said operating element 125

- adapted to engage with said inclined surfaces so as to move the said fingers inwardly so that they are capable of engaging with the head of the stud.
5. 4. In a stud-and-eye fastening a headed stud, a female member comprising a circular element and an annular element capable of relative axial movement the said member having a stud-receiving orifice, the circular element having a plurality of stud-engaging fingers, inclined surfaces formed on said stud-engaging fingers and resilient loops being formed therein between said surfaces and the operative ends of said fingers, means carried by said annular element adapted to engage with said inclined surfaces so as to force the ends of the stud-engaging fingers into operative position on movement of said element away from said stud-receiving orifice.
10. 5. In a stud-and-eye fastening a headed stud, a female member comprising a circular element and an annular element capable of relative axial movement, the said member having a stud-receiving orifice, the circular element having a plurality of stud-engaging fingers, inclined surfaces formed on said stud-engaging fingers and resilient loops being formed therein between said surfaces and the operative ends of said fingers, means carried by said annular element adapted to engage with said inclined surfaces so as to force the ends of the stud-engaging fingers into operative position on movement of said element away from said stud-receiving orifice, shoulders formed on said fingers directed towards said surface-engaging means adapted to secure said means against movement under light pressure or vibration.
15. 6. In a stud-and-eye fastening a headed stud, a female member comprising a circular element and an annular element capable of relative axial movement, the said member having a stud-receiving orifice, the circular element having a plurality of stud-engaging fingers, inclined surfaces formed on said stud-engaging fingers and resilient loops being formed therein between said surfaces and the operative ends of said fingers, means carried by said annular element adapted to engage with said inclined surfaces so as to force the ends of the stud-engaging fingers into operative position on movement of said element away from said stud-receiving orifice, shoulders formed on said fingers directed towards said surface-engaging means adapted to secure said means against movement under light pressure or vibration.
20. 7. In a stud and eye fastening, a female member comprising a body, an annular element slidable in said body, a central element floating in said annular element, stud engaging spring fingers carried by said central element, spring restoring means for the annular element, means operative on the depression of the annular element to release said stud engaging fingers from the engaging position, said means engaging the central element in the operation of the spring restoring means and serving to move said annular element and central element together, a subsequent depression of the central element causing the stud engaging fingers to be moved into the engaging position.
25. 8. In testimony whereof I affix my signature.
30. 35.

JOHN PHILIP MORSE.
